(57) **CLAIM**

The ornamental design for a surface pattern for sheet goods, as shown and described.

DESCRIPTION

The patent or application file contains at least one drawing executed in color. Copies of the patent or patent application publication with the color drawing will be provided by the office upon request and payment of the necessary fee.

The sole FIGURE is a view of a surface pattern for sheet goods. The broken line boundary of the sheet goods is for illustrative purposes only and form no part of the claimed design.
